Primary Examiner — Rosemary K Tarcza*(74) Attorney, Agent, or Firm* — Holzer Patel Drennan(57) **CLAIM**

The ornamental design for an earpiece charging case, as shown and described.

DESCRIPTION

FIG. 1 is a perspective view of an earpiece charging case showing our new design, as viewed from the top and front and with the charging case in a closed state.

FIG. 2 is a front elevational view thereof.

FIG. 3 is a back elevational view thereof.

FIG. 4 is a right side elevational view thereof.

FIG. 5 is a left side elevational view thereof.

FIG. 6 is a top plan view thereof.

FIG. 7 is a bottom plan view thereof.

FIG. 8 is a perspective view of the earpiece charging case, showing our new design, as viewed from the top and front and with the charging case in a closed state.

FIG. 9 is a front elevational view thereof.

FIG. 10 is a back elevational view thereof.

FIG. 11 is a right side elevational view thereof.

FIG. 12 is a left side elevational view thereof.

FIG. 13 is a top plan view thereof; and,

FIG. 14 is a bottom plan view thereof.

The broken lines depict portions of the earpiece charging case that form no part of the claimed design.
